UNITED STATES PATENT OFFICE.

JAKOB V. GUDMOND-HOYER, OF MORRIS, NEW YORK.

SUBSOILING APPARATUS.

1,125,018.

Specification of Letters Patent. Patented Jan. 12, 1915.

Application filed April 9, 1914. Serial No. 830,833.

To all whom it may concern:

Be it known that I, JAKOB V. GUDMOND-HOYER, a subject of the King of Denmark, residing at Morris, in the county of Otsego, 5 and State of New York, have invented certain new and useful Improvements in Subsoiling Apparatus, of which the following is a specification.

The present invention appertains in general to agricultural machinery and to that type of apparatus designed for breaking hardpan or subsoiling through the instrumentality of explosives, comprehending as its object the provision of suitable mechanism for drilling progressively holes in the ground to be operated upon, and depositing in said holes an explosive charge which is automatically fired when the apparatus has reached a predetermined point of safety.

20 In carrying out my invention, I preferably employ a motor vehicle on the forward portion of which is installed hole boring mechanism driven at will from the motor of said vehicle, while at the rear of the latter is arranged special charge firing mechanism consisting of a reel carrying a conductor which co-operates with an electric circuit to the extremity of which conductor is attached in turn by the operator an explosive cartridge which is dropped into a hole previously bored, and when the machine is at a safe distance said conductor brings into action a circuit closing member which automatically closes the electric circuit and fires 30 the explosive charge.

A further object is to provide a plurality of such reels to permit the disposition of a series of charges, each of which is successively fired at predetermined times controlled by the movement of the vehicle whereby a continuous operation of depositing and explosion of the charges may be effected.

45 A further object of this invention is to provide actuating means for the reel or reels whereby the conductor after depositing the explosive cartridge and being paid out to a predetermined extent may be quickly rewound upon the reel to enable replanting of 50 a subsequent charge.

These and such other objects as may hereinafter appear are attained by the novel con-

struction, combination and arrangement of parts to be hereinafter specifically described and claimed.

55 Reference will now be had to the accompanying drawings forming a part of this specification, wherein:

Figure 1 is a side elevation of an apparatus constructed in accordance with my invention. Figs. 2 and 3 are front and rear elevations, respectively, of the same. Fig. 4 is an enlarged detail view of the clutch operating mechanism for the drilling tool employed in the apparatus. Fig. 5 is a sectional view on 60 the line 5—5 of Fig. 4. Fig. 6 is an enlarged view in elevation of the charge firing mechanism used in my apparatus. Fig. 7 is a detail fragmentary view in elevation of the vehicle stopping mechanism for automatically bringing said vehicle carrying the mechanisms of my invention to a stop at predetermined points; and Fig. 8 is a horizontal sectional view on the line 8—8 of Fig. 7.

70 Referring to the drawings and specifically 75 describing my invention the numeral 1 designates a motor vehicle, 2 the motor therefor, 3' the driving shaft operatively connected through the driving chains 4 to the rear driving wheels 5. It will be understood that 80 any desired design of vehicle may readily be used in carrying out this apparatus, and I do not wish to be strictly confined with respect to the details shown in the accompanying illustrations, it being preferable, however, 85 that the vehicle be of a predetermined length to best carry out the operation, as will be hereinafter more fully disclosed. Arranged at the forward extremity of the vehicle is the boring or drilling mechanism comprising 90 a vertically disposed toothed lifting bar or rack 6, operable by means of a hand wheel 7 located adjacent to the driver's seat 8 and the steering column 9, said wheel being carried by the shaft 10 which has at its outer 95 end the pinion 11 meshing with the lifting bar 6.

100 Referring particularly to Fig. 4 of the drawings it will be noted that the lower extremity of the bar 6 is loosely connected to the upper extremity of a bit or auger or other suitable drilling tool 12, the connection permitting free rotation of said auger during movement of the same by said lift-

ing bar. The auger is driven by means of the shaft 3 which is geared with the driving shaft 3' having a beveled pinion 13 at its extremity intermeshing with a similar pinion 14 on a vertical shaft 15 supported in arms 16 of the depending frame 17 and the lower end of the shaft 15 carries a gear 18 intermeshing with a relatively sliding gear 19 of the clutch element 20. The upper extremity of said clutch element is preferably frusto-conical in shape and extends into a coöperating clutch element 21 which has an internal lug 21' movable in a groove 22 extending longitudinally of the auger, as clearly shown in Figs. 4 and 5 of the drawings, and the lower end of the element 20 has loose connection with the headed extremity of the lifting lever 23 pivotally mounted at 24 on the frame 17. The opposite end of said lever is connected to a foot lever 25, so that it will be obvious upon depression of the foot lever 25 the clutch element 20 will be raised until it frictionally engages the element 21 operatively connected to the auger 12, thereby communicating rotation imparted to the clutch element 20 by the shaft 3 to said auger. The auger is operated to drill a hole the proper depth by means of the hand wheel 7 which lowers or raises the bar 6. In actual use the holes in the ground to be operated upon are bored at predetermined distances apart and any suitable means may be employed by which to determine the interval between said holes, as hereinafter described.

Upon the rear extremity of the vehicle is located the charge firing mechanism of this apparatus and a supporting frame 26 is provided in which I mount a horizontal shaft 27 loosely carrying a plurality of spools or reels 28 there being any desired number of such reels but as illustrated in the drawings, I employ five of the same. The shaft 27 is operatively connected with the driving axle of the vehicle through the instrumentality of the driving chains 29 so that during operation or movement of the vehicle the shaft is caused to revolve. Upon each of these reels is wound a conductor or what I specifically term a leading wire 30 of suitable size and length for properly performing the function now to be described. The free extremity of each of the conductors 30 has connected thereto a drag weight 31 and they pass downwardly through suitable insulated openings of a guiding bar 32 of material which will properly conduct an electric current the circuit in which said bar is included leading from a suitable source such as the batteries 33.

With the foregoing in mind, and assuming that the apparatus is to be operated, the operator on the forward seat, by manipulation of the auger drills a hole, and then advances the vehicle the length of the same or until

the hole is directly beneath an opening in the floor or bottom of said vehicle adjacent the rear seat 34. The second operator on this seat extracts a cartridge 36' of explosive 35, such as dynamite ordinarily used in work of this character, from the magazines 36 at either side of the rear portion of the machine and placing the usual cap in said cartridge connects the same by a short piece of fuse wire 37 to the drag weight 31 of the first or right-hand reel, see Fig. 6. Lowering the cartridge through the conductor guiding member 32 until it is properly deposited in the hole in the ground beneath his feet, he opens a door 38 at the lower extremity of a chute 39 leading from the compartment 40 between the rear seat 34 and the motor 2 which contains the tamping material, permitting a sufficient amount of such material which preferably consists of marl, to drop upon the cartridge. This material is then tamped by any suitable instrument such as a plunger or stick and the machine moves forward to the next hole where the operation is repeated with respect to the second reel, and so on until the five cartridges have been planted.

Assuming for the sake of illustration that the distance between each hole bored is 15 feet, when the fifth cartridge has been deposited the first one will be some sixty feet away, the second forty-five, etc., and as the first conductor or wire 30 has approximately played out its full length controlled by movement of the vehicle a metallic bridging member or circuit closer 41 connected to said conductor is pulled down upon the guiding bar plate 32' in such a manner as to span the insulated opening through which said wire passes, thereby closing the electric circuit and firing the first cartridge connected to its extremity. The circuit for the electric current by means of which the explosive charge is fired may be arranged in any convenient manner but it is preferable that the reels or spools 28 should be of a non-conducting material and that the guiding bar 32 be supported on the frame 26 by insulating supports 32'' insuring that the current will flow from one terminal of the battery through the guide bar and the proper leading wire to the cartridge and from the ground through the vehicle wheels to the other terminal of the battery. Such firing takes place progressively as the machine advances over the ground and the respective circuit closing members of each wire are brought into contact with the guiding bar 32. As the machine is moved toward the next hole the operator shifts a lever 42 laterally and throws a clutch 43 connected to the shaft 27 into contact with the coöperating reel 28 causing said reel to be actuated and the wire 30 of that reel to be rewound upon the same.

It will be understood and as shown in

Figs. 3 and 6 of the drawings, that each of the reels is provided with a clutch and lever to enable rewinding of the respective conductors thereupon so that a new cartridge

5 may be connected to the drag weight as the free end arrives in position for the rear operator to handle the same.

As hereinbefore mentioned I preferably employ in conjunction with this apparatus 10 means for automatically bringing the motor vehicle to a stop at predetermined points so as to enable the drilling of the openings in the ground by the auger at regular intervals thus, furthermore, insuring that the openings 15 will come successively to a point beneath the operator at the rear of the machine to permit him to deposit in the openings the explosive charge. Such mechanism preferably consists of a cam wheel 44 mounted upon a shaft 45 journaled in a standard 20 46 near the forward extremity of the machine, which shaft is driven through the driving chains 47, 48 from the vehicle driven shaft 3', as shown most clearly in Fig. 1 of the drawing. The cam wheel 44 is provided 25 with a grooved periphery as indicated at 48, a portion of said groove, at one side of the wheel, being deeply cut out as indicated at 49 in Fig. 8 of the drawings. Secured to the 30 frame of the vehicle adjacent the cam wheel 44 is an operating lever 50 normally held in the groove 48 of the cam wheel by means of a spring 51, the lower end of said lever being connected to the brake rod 52 passing to the 35 brake 53 on the rear driving axle of the vehicle.

At 54, (see Fig. 8) is denoted a projecting lug on the cam wheel 44, and the purpose of the same will now be described. The size of 40 the cam wheel 44 or the ratio of its connection with the drive shaft of the motor vehicle is such that one revolution of this wheel represents the proper interval between 45 a pair of openings which are made by means of the drilling mechanism. When a hole has been made in the ground by the drilling member 12 the operator of the vehicle moves the operating lever 50 on its pivot so as to engage the same on the lug 54 of the cam 50 wheel and throwing in his clutch the vehicle will move forwardly causing rotation of the cam wheel by reason of its connection with the vehicle drive shaft. When the wheel 44 has substantially rotated a single rotation, 55 the lever moving around the groove 48 reaches the deep portion of the groove 49 and under actuation of the spring 51 applies the brake to the vehicle through the operative connection 52 and brings the vehicle 60 to a stop automatically so that the hole drilled as just mentioned will be properly located beneath the opening at the rear portion of the vehicle to enable the deposit of the explosive cartridge. Obviously the 65 details of this arrangement may be changed

within the purview of this invention and the scope of the claims hereto appended.

Having thus described the invention what I claim as new is:

1. In subsoiling apparatus of the class described, the combination of a vehicle, means for depositing an explosive charge, an electric circuit, and means operable by the depositing means for closing the circuit to fire the charge. 75

2. In subsoiling apparatus of the class described, the combination of a vehicle, means for depositing an explosive charge, an electric circuit, and means automatically operable by the depositing means for closing the 80 circuit to fire the charge at a predetermined time.

3. In subsoiling apparatus of the class described, the combination of a vehicle, means for depositing an explosive charge, an electric circuit, and means operable by the depositing means and controlled by movement 85 of the vehicle for closing the circuit to fire the charge.

4. In subsoiling apparatus of the class described, the combination of a vehicle, hole boring means carried by said vehicle, an electric circuit, means for depositing an explosive charge in the holes bored by the drilling means aforesaid, and means operable by the last mentioned means to close 90 said circuit and fire the charge at a predetermined time. 95

5. In subsoiling apparatus of the class described, the combination of a vehicle, charge 100 firing mechanism carried thereby and including a conductor to which a charge is connected for disposition at a predetermined point, and a circuit closing member co-operating with the conductor for firing the 105 charge at a predetermined point.

6. In subsoiling apparatus of the class described, the combination of a vehicle, charge 110 firing mechanism carried thereby and including a conductor to which a charge is connected for disposition at a predetermined point and adapted to be paid out on movement of the vehicle, and means controlled by the movement of said vehicle for firing the charge when the vehicle has reached a 115 predetermined distance from said charge.

7. In subsoiling apparatus of the class described, the combination of a vehicle, charge 120 firing mechanism carried thereby including an electric conductor to which a charge is connected for disposition at a predetermined point, an electric circuit normally broken in which said conductor is included, a circuit closing member connected to the conductor and adapted to automatically close the electric circuit at a predetermined point of paying out of the electric conductor to fire the charge when the vehicle has reached a 125 proper distance away from the deposited charge. 130

8. In subsoiling apparatus of the class described, the combination of a vehicle, hole boring mechanism carried by said vehicle, means for depositing a charge in a hole bored by the mechanism aforesaid, said means consisting of a conductor reeled upon the vehicle to the end of which an explosive charge is adapted to be connected, means for guiding the conductor in depositing the charge, an electric circuit in which said last-mentioned means is included, said guiding means maintaining the electric circuit normally out of electric connection with the conductor aforesaid, and a circuit closing member operable by the conductor at a predetermined point in its unwinding to close the circuit and fire the charge when the vehicle has moved away from the same a proper distance.
- 10 9. In subsoiling apparatus of the class described, the combination of a vehicle, hole boring mechanism carried thereby, charge firing mechanism on said vehicle comprising a reel, a shaft carrying said reel and operably connected for actuation by the vehicle, a conductor member wound upon the reel to which a charge is adapted to be connected for disposition in a hole bored by the boring mechanism aforesaid and to be paid out as the vehicle moves away from the point of deposit, and means for rewinding the conductor after firing the charge.
- 15 10. In subsoiling apparatus of the class described, the combination of a vehicle, hole boring mechanism carried thereby, charge firing mechanism mounted on said vehicle and comprising a reel, a shaft on which said reel is loosely mounted, driving means for said shaft whereby to actuate the same during movement of the vehicle, a leading wire wound upon said reel and to the end of which is adapted to be connected an explosive charge, a guiding member associated with the leading wire for facilitating depositing of the explosive charge, said wire being adapted to unwind from said reel as the vehicle is moved, clutch means carried by the shaft for interlocking the reel to move therewith, and means for operating said clutch means whereby to rewind the wire upon said reel when said shaft is actuated.
- 20 11. In subsoiling apparatus of the class described, the combination of a vehicle, boring mechanism carried thereby for drilling holes at predetermined points, charge firing mechanism on said vehicle and comprising a plurality of reels, a shaft on which said reels are loosely mounted, conductor members wound upon said reels, to the extremities of which explosive charges are adapted to be connected for depositing said charges in holes bored by the boring mechanism aforesaid, an electric circuit, a guiding member included in said circuit and having insulated openings therein through which the conductors aforesaid pass, and means actuated by said conductors for closing the circuit aforesaid and the conductor whereby to fire the charge at predetermined points.
- 25 12. In subsoiling apparatus of the class described, the combination of a vehicle, boring mechanism carried thereby, charge firing mechanism on said vehicle, comprising a plurality of reels to which is adapted to be connected an explosive charge, a guide member associated with said reels, and having insulated openings through which the wires aforesaid pass, an electric circuit in which said guide member is included, a circuit closing member carried by each of the aforesaid leading wires and adapted to be actuated by the same as the wire is paid out during movement of the vehicle and to cooperate with the guide member aforesaid to close the electric circuit and cause the current to flow through the leading wire to the explosive charge connected to said wire for firing the same at a predetermined point in the paying out of said leading wire, and means for rewinding the wires on said reels after the charges have been fired.
- 30 13. In subsoiling apparatus of the class described, the combination of a vehicle, charge firing mechanism carried thereby, an electric circuit, a conductor member to which an explosive charge is adapted to be connected and to be paid out for deposit and normally insulated from said electric circuit, and means connected to the conductor for actuation thereby at a predetermined point in its length to automatically close said electric circuit and cause passage of the current through said conductor to the charge for firing the same.
- 35 14. In subsoiling apparatus of the class described, the combination of a vehicle, charge firing mechanism carried thereby, an electric circuit, a conductor member to which an explosive charge is adapted to be connected and to be paid out for deposit, means normally maintaining the conductor disconnected from said electric circuit, and a circuit closing member adapted to cooperate with the last mentioned means to automatically close the circuit and fire the charge upon paying out of a predetermined length of said conductor member.
- 40 15. In subsoiling apparatus of the class described, the combination of a vehicle, means for propelling said vehicle, charge firing mechanism carried by said vehicle, said mechanism comprising explosive depositing means, and means for automatically controlling the stoppage of said vehicle whereby the explosive charges may be deposited at regular intervals.
- 45 16. In subsoiling apparatus of the class described, the combination of a vehicle, charge firing mechanism carried thereby and

including means for depositing explosive charges, brake mechanism for said vehicle, and means for applying the brake at predetermined points in the movement of said vehicle whereby the explosive charges may be deposited at predetermined points in the movement of said vehicle.

In testimony whereof I affix my signature in presence of two witnesses.

JAKOB V. GUDMOND-HOYER.
